CAN UNSCRAMBLING DEVICE

Verro Ashel Harris, Monterey, Calif., assignor to
 California Packing Corporation, San Francisco,
 Calif., a corporation of New York

Application August 26, 1946, Serial No. 693,072

8 Claims. (Cl. 198—43)

1

This invention relates to can handling machinery, and more particularly to a device adapted to receive cans positioned indiscriminately either right side up or upside down and conduct the right side up cans through an independent path and simultaneously conduct the upside down cans through a second independent path and present both types of cans to a conveyer belt in right side up position.

The device of the present invention is particularly designed for the handling of sardine cans and makes use of the fact that such sardine cans are provided adjacent their upper sides with a peripheral seam. It is necessary to present these cans in right side up position to the conveyer belt on which they are to be conveyed to the can labeling machine.

It is accordingly one object of this invention to provide a device for handling cans indiscriminately positioned either right side up or upside down to rearrange the cans so that all are presented to a conveyer belt in upright position.

It is a further object of this invention to provide such a device utilizing a gravity feed.

It is a further object of this invention to provide means to conduct cans having an initially upright position through one canway wherein they are maintained in their upright position and cans having an initially upside down position through another canway in which they are turned over and to lead both of said canways to a common conveyer mechanism.

It is a further object of this invention to provide means whereby cans may be fed from either of said canways to said common conveyer means without interfering with each other or piling up.

It is a feature of this invention that cans presented to the unscrambling machine in an upright position are contacted adjacent the peripheral seam and conducted through a spiral canway to a conveyer belt, whereas cans presented to the unscrambling machine in an upside down position are not engaged by their seams and do not travel through the spiral canway but instead travel through a looped canway in which their position is reversed before being presented to their conveyer means.

It is a further feature of this invention that the bottom ends of both canways are provided with means whereby a can being fed from one canway to the belt must clear the mechanism before a can can be fed to the belt from the other canway.

Further objects, advantages and features ap-

2

pear in the hereinafter annexed specification in which:

Figure 1 is a side elevation of a device embodying the present invention.

Figure 2 is a rear elevation of the device shown in Figure 1.

Figure 3 is a plan view of the device shown in Figure 1.

Figure 4 is an end elevation of the entering section of the device illustrating the reception of a can in the upright position and also illustrating a can in the inverted position.

Figure 5 is a fragmentary side elevation similar to Figure 1 showing the can chute mechanism in an alternate position.

Referring more particularly to the drawings, there is shown a can unscrambling machine indicated generally at 10 and including an upstanding frame member 12 comprising a pair of vertically extending angle irons 13 connected substantially midway of the machine by a stiffening plate 14. Adjacent the upper end of the frame, a pair of side frames 15 are provided, each welded or otherwise secured to the flat side of its angle iron 13. Welded to the top edge of each of the side pieces 15 is the bottom member 16 of a looped canway. The bottom member 16 is provided at its upper end with a depending flange 17 to serve as a guard. In spaced relation to the bottom member 16 of the canway are a pair of rails 18 secured as by means of bolts 19 and spacing tubes 20 to the bottom member 16. By reference to Figure 1 it will be noted that the bottom member 16 of the canway describes a substantially semicircular loop and that the bottom end of the machine becomes the top of the canway as indicated at 21. The spaced rails 18 describe a similar loop as indicated at 22. Both the bottom member 16 and the rails 18 have a straight portion and a curved portion. Where the curved portion of these rails begin, the canway is provided with an outer member 23 secured to the member 16 by means of bolts 24. Within this section of the canway the bolts 24 are provided with a pair of spacers 25 and 26 located respectively between the member 23 and the rails 18, and the rails 18 and the bottom member 16, thus the bolts 24 and the spacers 25 and 26 serve to support both the rails 18 and the outer member 23 throughout this section of the machine.

The device is provided at the upper end thereof with a pair of rails 28. The rails 28 are secured to the bottom member 16 by means of bolts 29 and spacers 30. By reference to Figure 4, it will be noted that the rails 28 are beveled upon their

inner edges as at 31 and extend inwardly beyond the inner edges of the rails 18.

The device is provided, adjacent its upper end, with a bracket 34. The bracket 34 carries a pair of screws 35 in each of its sides, the ends of which are welded to or otherwise suitably support the rails 28. The bracket 34 also carries through its upper wall a screw 36, the bottom end of which is welded to or otherwise suitably supports a top guard 38. The top guard 38 is carried in spaced relation above the rails 28 and has an upwardly bent entering section 39, as indicated in Figure 1.

The device is also provided with a second bracket 40 secured to the bottom member 16 by means of bolts 41. The bolts 41 also support at this position the rails 28 and an additional pair of rails 42. The bracket 40 carries a pair of screws 43, the inner edges of which are welded to or otherwise suitably support the rails 28 and the upper wall of the bracket 40 carries a screw 44, the lower end of which is welded to or otherwise carries the top guard 38. Spaced from the rails 42 by means of bolts 45 are spacers 47 and a pair of rails 48. By reference to Figures 1 and 3, it will be noted that the rails 42 and 48 follow a spiral pathway as indicated.

Adjacent the bottom of the machine a pair of side plates 50 are welded or otherwise suitably secured to the frame member 12. The rails 48 are welded to the beveled top member of the side plates as indicated at 51. The rails 42 extend beyond the side plates 50 in the portion indicated at 52. A chute 54 is provided having a pair of pin receiving bosses 55 into which are rigidly secured the inward ends of counterweight levers 56. The inward ends of the counterweight levers 56 pass through the side frames 50 and are pivotally supported thereby. The outer ends of the levers 56 are provided with counterweights 57. The chute 54 is built in the form of a channel and attached to the bottom thereof is a skid 58. The skid 58 has a brace 59 attached to the bottom of the chute 54 and to a flat member 60 constituting the bottom of the skid. The member 60 has an upwardly bent end member 61.

The chute 54 is also provided substantially midway thereof with a handle 62 in which is pivotally mounted one arm of a U-shaped hinge pin 63, the other arm of which is positioned in a boss 64 formed on the can stop 65. The can stop 65 is pivoted as at 66 from the frame member 12 and includes a straight portion 67, an upwardly bent arm 68 and a depending skid 69. The skid 69 is welded to the bottom of the can stop 65 and includes a flat portion 70, an intermediate portion 71 and an angularly disposed portion 72 as indicated in Figure 1.

The device above described is adapted to be used in connection with a conveyer belt 80 which is independently mounted. The conveyer belt 80 passes under and in close proximity to the bottom end of member 23 and further passes under and in close proximity to the lower edge of the chute 54 when the chute 54 is in its downward position. The conveyer belt is supported adjacent the above described machine by means of a channel member 81 which may be secured to the bottom of the frame 12 and the side plate 50 by welding it thereto.

Referring now to Figure 4 in the upper section of this figure there is shown a can 90 in the inverted position as it enters the machine. With the can thus inverted the flange 91 of the can is not engaged by the rails 28, but the can is confined between the rails 18 and the bottom member

16 and prevented from leaving the canway. The can 90 will therefore pass down the looped canway formed by the rails 18, the bottom member 16 and the outer member 23, and will be inverted and presented to the belt 80 as indicated in the bottom of Figure 1.

Referring again to Figure 4, in the lower portion thereof there is shown the can 100 in the upright position. It is noted that the bottom of this can is riding on the bottom member 16 but that the flange 101 of the can is engaged by the inwardly extending edges of the rails 28. This can will therefore follow the rails 28 through the spiral canway in which case it is not inverted but is presented to the can chute 54 as indicated in the bottom of Figure 1.

While it is not illustrated, it will be understood by those skilled in the art that cans are fed by a suitable conveyer mechanism to the entering section of the machine. It will further be understood that these cans may be either in the inverted position as shown in 90 or in the upright position as shown in 100. It will further be understood that these cans are fed continuously into the machine, and in order to prevent piling up or interference by the cans from the various canways, the above-described can stop and chute are provided.

Referring more particularly to Figures 1 and 5, it will be noted that, when a can is placed upon the chute 54, the weight of the can overbalances the counterweights 57 and causes the chute 54 to tilt downwardly until the skid 58 contacts the belt 80. The can placed on the chute 54 will therefore be passed to the belt 80. As shown in Figure 1, when the chute 54 is in this downward position, the can stop 65 is so positioned that the skid 69 is forced downwardly so that the angular portion 72 thereof is in a position to stop any can coming down the looped canway and prevent this can from interfering with the cans from the chute 54. By reference to Figure 5, however, it will be noted that when a can has passed down the looped canway and under the skids 69 and 58, the chute 54 is held in a raised position by the underlying can, and furthermore the upwardly extending arm 68 of the can stop 65 is in a position to stop any can on the can chute. Thus, cans from the chute 54 are prevented from interfering with cans from the looped canway.

While there has been described what is at present considered the preferred embodiments of the invention, it will be understood that various changes and alterations may be made therein without departing from the essence of the invention that is intended to cover herein all such changes and alterations as come within the true scope and spirit of the annexed claims.

I claim:

1. A can handling device adapted to receive a continuous supply of cans of the type having flanged seams adjacent the upper edge thereof, part of which may be inverted and to discharge said cans all in upright position comprising a canway to which said cans are presented, a pair of rails spaced from said canway to engage the flange of the upright cans and discharge them without inverting, a looped canway adapted to invert and discharge said inverted cans and a conveyer belt to which all of said cans are discharged, the paths of said rails and of said looped canway converging so as to discharge all of said cans to said conveyer belt traveling in substantially the same direction and means for prevent-

ing the discharge of cans from said rails when a can is discharging from said looped canway.

2. A can handling device adapted to receive a continuous supply of cans of the type having flanged seams adjacent the upper edge thereof, part of which may be inverted and to discharge said cans all in upright position comprising a canway to which said cans are presented, a pair of rails spaced from said canway to engage the flange of the upright cans and discharge them without inverting, a looped canway adapted to invert and discharge said inverted cans, and a conveyer belt to which all of said cans are discharged, the paths of said rails and of said looped canway converging so as to discharge all of said cans to said conveyer belt traveling in substantially the same direction and means for preventing the discharge of cans from said looped canway when a can is discharging from said rails.

3. A can handling device adapted to receive a continuous supply of cans of the type having flanged seams adjacent the upper edge thereof, part of which may be inverted and to discharge said cans all in upright position comprising a canway to which said cans are presented, a pair of inclined rails spaced from said canway to engage the flange of the upright cans and discharge them without inverting, said rails having a spiral path, and a looped canway adapted to invert and discharge said inverted cans, said looped canway including upper and lower walls and a pair of side rails for confining the cans during inverting, and a conveyor belt to which all of said cans are discharged, the paths of said rails and of said looped canway converging so as to discharge all of said cans to said conveyer belt traveling in substantially the same direction and means for preventing the discharge of cans from said rails when a can is discharging from said looped canway.

4. A can handling device adapted to receive a continuous supply of cans of the type having flanged seams adjacent the upper edge thereof, part of which may be inverted and to discharge said cans all in upright position comprising a canway to which said cans are presented, a pair of inclined rails spaced from said canway to engage the flange of the upright cans and discharge them without inverting, said rails having a spiral path, a looped canway adapted to invert and discharge said inverted cans, said looped canway including upper and lower walls and a pair of side rails for confining the cans during inverting and a conveyer belt to which all of said cans are discharged, the paths of said rails and of said looped canway converging so as to discharge all of said cans to said conveyer belt traveling in substantially the same direction and means for preventing the discharge of cans from said looped canway when a can is discharging from said rails.

5. A can handling device adapted to receive a continuous supply of cans of the type having flanged seams adjacent the upper edge thereof, part of which may be inverted and to discharge said cans all in upright position comprising a canway to which said cans are presented, a pair of rails spaced from said canway to engage the flange of the upright cans and discharge them without inverting, a looped canway adapted to invert and discharge said inverted cans, the paths of said rails and of said looped canway converging so as to discharge all of said cans traveling in substantially the same direction, a pivoted can chute associated with said rails and a counterbalance for said can chute biasing said can chute

normally to inoperative position and skid means associated with said chute and engageable with a can discharging from said looped canway for retaining said chute in said inoperative position where a can is discharging from said looped canway.

6. A can handling device adapted to receive a continuous supply of cans of the type having flanged seams adjacent the upper edge thereof, part of which may be inverted and to discharge said cans all in upright position comprising a canway to which said cans are presented, a pair of rails spaced from said canway to engage the flange of the upright cans and discharge them without inverting, a looped canway adapted to invert and discharge said inverted cans, the paths of said rails and of said looped canway converging so as to discharge all of said cans traveling in substantially the same direction, a pivoted can chute associated with said rails and a counterbalance for said can chute biasing said can chute normally to inoperative position, said means associated with said chute and engageable with a can discharging from said looped canway for retaining said chute in said inoperative position where a can is discharging from said looped canway and a pivoted can stop adapted to stop a can reaching said chute when in said inoperative position.

7. A can handling device adapted to receive a continuous supply of cans of the type having flanged seams adjacent the upper edge thereof, part of which may be inverted and to discharge said cans all in upright position comprising a canway to which said cans are presented, a pair of rails spaced from said canway to engage the flange of the upright cans and discharge them without inverting, a looped canway adapted to invert and discharge said inverted cans, the paths of said rails and of said looped canway converging so as to discharge all of said cans traveling in substantially the same direction, a pivoted can chute associated with said rails and a counterbalance for said can chute biasing said can chute normally to inoperative position, skid means associated with said chute and engageable with a can discharging from said looped canway for retaining said chute in said inoperative position where a can is discharging from said looped canway, a pivoted can stop adapted to stop a can reaching said chute when in said inoperative position and said counterbalance being of insufficient mass to bias said can chute to said inoperative position when a can is stopped thereon, whereby said can chute may pivot to operative position when freed by said skid means.

8. A can handling device adapted to receive a continuous supply of cans of the type having flanged seams adjacent the upper edge thereof, part of which may be inverted and to discharge said cans all in upright position comprising a canway to which said cans are presented, a pair of rails spaced from said canway to engage the flange of the upright cans and discharge them without inverting, a looped canway adapted to invert and discharge said inverted cans, the paths of said rails and of said looped canway converging so as to discharge all of said cans traveling in substantially the same direction, a pivoted can chute associated with said rails and a counterbalance for said can chute biasing said can chute normally to inoperative position, skid means associated with said chute for retaining said chute and engageable with a can discharging from said looped canway in said inoperative position where a can is discharging from said looped canway, a

pivoted can stop adapted to stop a can reaching said chute when in said inoperative position, said counterbalance being of insufficient mass to bias said can chute to said inoperative position when a can is stopped thereon, whereby said can chute may pivot to operative position when freed by said skid means and a can stop associated with said looped canway operative to prevent the discharge of cans from said looped canway when said can chute is in operative position.
